Fraseritor.
By George J. Knight
The Fifth

UNITED STATES PATENT OFFICE.

JOHN SCHULZ, OF CHICAGO, ILLINOIS.

HUMIDIFIER.

Application filed May 24, 1923. Serial No. 641,029.

This invention relates to improvements in humidifiers.

The object of the invention is to provide a simple and efficient humidifier especially adapted for use in connection with heating apparatus, such as steam or hot water radiators with a register of a hot air system, wherein the supply of water is gradually fed by gravity to the vaporizing means.

More especially, an object of the invention is to provide a device of the character indicated, wherein is employed a supporting frame having a horizontally disposed wick associated therewith and a water containing reservoir located above the wick, together with means co-operating with said device to automatically feed water from the reservoir to the wick.

Other objects and advantages of the invention will more clearly appear from the description and claims hereinafter following.

In the drawing forming a part of this specification Fig. 1 is a plan view of my improved humidifier. Fig. 2 is a longitudinal, vertical, sectional view, corresponding substantially to the line 2—2 of Fig. 1. Fig. 3 is a transverse, vertical, sectional view, partly broken away, corresponding substantially to the line 3—3 of Fig. 1. Fig. 4 is a detail perspective view of a wire supporting frame used in connection with the device.

In said drawing 10 denotes a rectangular sheet metal frame comprising vertical side walls 11—11 and end walls 12—12. At their upper edges the walls 11 and 12 are provided with inwardly projecting, horizontal flanges 13 rigidly connected at the corners of the frame in any suitable manner, as by being soldered, to provide in effect a continuous flange. The end walls 12 are cut away at their lower sides as clearly shown in Fig. 3, and the lower edges of the side walls 11 are provided with inwardly projecting horizontal flanges 14, for a purpose hereinafter described.

A rectangular wire screen 15, of a size to fit the interior of the frame 10, is permanently attached to the top of the frame by having the edge portion thereof soldered or otherwise secured to the lower faces of the flanges 13. The screen 15 is provided with a central opening adapted to receive a screw threaded sheet metal ring 16 provided with a peripheral flange 17 extending over the upper surface of the screen at the edge of the opening and rigidly secured thereto in any

suitable manner, preferably being soldered. The ring 16 is also braced and supported by a pair of spaced sheet metal strips 18 of angular cross-section, extending transversely of the frame, beneath the screen 15 and rigidly secured to the lower faces of the flanges 13 of the opposite side walls 11 and to the opposite sides of the ring, in any suitable manner, preferably by being soldered thereto. The strips 18 also serve to support the central portion of the screen 15 and have the upper flanges thereof soldered to the screen adjacent the point at which the ring is attached thereto.

A second rectangular wire screen 19, of a size to fit the interior of the frame, is supported below the screen 15 by means of a rectangular wire supporting frame 20, having three legs 21, of similar construction, and a fourth leg 22 of somewhat different design.

The supporting frame 20, as most clearly shown in Fig. 4, is formed of a continuous wire, the legs 21 being formed by downwardly extending loops at three corners and the leg 22 being formed by downwardly extending portions 23 and 24 bent at their lower ends to provide feet 25, the portions 23 and 24 forming the opposite end terminals of the wire. The legs 21 and 22 are adapted to rest on the flanges 14 of the frame and the peripheral portion of the screen 19 is loosely supported by the upper horizontal portion of the wire frame 20.

The screen 19 is provided with an opening concentric with the opening in the upper screen 15 and adapted to receive a shallow cup 26, provided with a peripheral horizontal flange 27 projecting over the top of the screen 19 and permanently secured thereto, in any suitable manner, preferably by being soldered. The cup 26 is of greater diameter than the ring 16 so that the ring extends into the same when the parts are assembled.

A flat wick 28 of rectangular shape is supported upon the screen 19 as clearly shown in Fig. 3, the wick 28 is continuous and extends into the cup 26 and over the bottom thereof. The wick 28 may be of any suitable design and construction, but is preferably of open mesh fabric.

A reservoir 29 for the supply of water is supported by the frame 10, above the cup 26. The reservoir 29, herein illustrated, is in the form of a glass receptacle, preferably a common "Mason jar" provided with an internally and externally screw threaded sheet

metal cap 30, having an opening 31 through which the water may pass, the jar being arranged in inverted position and having the cap thereof screwed into the ring 16. As 5 clearly shown in Fig. 3, the parts are so proportioned that the cap 30 extends an appreciable distance into the cup 26 when the parts are assembled, so that the lower face of the cap rests on the wick and is at a level a substantial distance below the upper rim of the 10 cup.

In assembling the parts, the screen 19 with the wick 28 thereon, is first inserted through the bottom of the frame. The wire support 20 is then placed in position by inserting the same through the bottom of the frame. It will be evident that the frame 20 may be contracted, by springing in the three sides thereof by forcing the ends of the sides adjacent the leg 22 inwardly, inward movement thereof being permitted due to the fact that the parts 23 and 24 are arranged in loosely abutting relation. The support 20 may, therefore, be easily inserted and spread apart, so that the legs 21 and 22 will rest on the supporting flanges 14 of the frame 10. The screen 19 may be easily removed at will, to renew the wick 28 by contracting the support 20 and removing the same, as 30 hereinbefore described.

The operation of my improved humidifier is as follows. The reservoir 29 is first filled with water and the cap 30 screwed into place thereon. The reservoir 29 is then attached 35 to the frame while the latter is in inverted position, by screwing the cap 30 into the ring 16. The frame 10 and the reservoir 29 attached thereto is then turned over, so that the frame is right side up and the jar forming the reservoir 29 is in inverted position. With the parts in this position the device is placed on a radiator or any other heating device. In this position of the parts, the water will flow by gravity through the 40 opening 31 of the cover 30 gradually filling the cup 26. Over-flowing of the cup will be prevented by the action of the atmospheric pressure on the surface of the water in the cup 26, sustaining the column of water in the reservoir a partial vacuum being created 45 in the upper part of the reservoir. The water is drawn up into the wick from the cap by capillary action, thereby causing the entire wick to become thoroughly saturated. 50 The device may be placed in position with reference to a radiator or other heating apparatus, so that heated air may pass through the open bottom of the frame, the screen 19, wick 28 and screen 15 vaporizing the water 55 in the wick, and thereby humidifying the air. As vaporization takes place, the supply will be replenished from the cup 26 by capillary action of the wick 28. The supply 60 of water in the cup 26 will remain at a substantially constant level, being fed by the

reservoir 29, the tendency being, as the level in the cup drops, for the water to flow from the reservoir, through the opening 31 in the cap thereof, due to the action of gravity, balanced by the atmospheric pressure on the surface of the water in the cup. The supply of water in the cup is thus automatically replenished as it is drawn out by the wick. 70

It will be evident that the cap 30 may be entirely omitted and the device work equally well, but I prefer to provide a perforated cap for closing the mouth of the reservoir, so that the reservoir may be assembled with the frame and the parts more easily inverted 80 and handled without danger of spilling the water. It will also be evident that the perforation 31 serves as a means for controlling the rate of flow of the water from the reservoir, the same being preferably of 85 the proper size to supply the correct amount of water in a given time.

I have herein shown and described what I now consider the preferred manner of carrying out the invention, but the same is 90 merely illustrative and I contemplate all changes and modifications that come within the scope of the claims appended hereto.

I claim:

1. In a device of the character described, the combination with a supporting frame; of a receptacle supported by said frame, said receptacle being open at the top; a porous member adapted to absorb water by capillary action, said member having a portion thereof extending into said receptacle to withdraw the water therefrom and having other substantially horizontally disposed portions extending exteriorly of said receptacle; and means for supplying water to said receptacle, including a closed reservoir disposed above said receptacle having outlet means communicating with said receptacle, said outlet means extending into the receptacle below the open top thereof. 100

2. In the device of the character described, the combination with an open supporting frame; of a screen supported at the top of said frame; a second screen supported in said frame below said first named screen; a cup supported by said last named screen; a wick of absorbent material extending over said last named screen and projecting into said cup; and a receptacle closed at the top and open at the bottom supported by said frame above said wick, said receptacle having the bottom thereof extending through said first named screen and projecting into said cup, with the opening thereof disposed below the upper edge of said cup. 115

3. In a device of the character described, the combination with a rectangular frame open at the top and bottom; of a screen supported at the top of the frame, said screen having a central opening therethrough; a 120

- screw threaded ring disposed in said opening supported by a pair of members secured to the frame; a second screen removably mounted in said frame below said first named 5 screen, said last named screen being supported by a removable support; a cup and a wick rigidly supported by said last named screen said wick extending into said cup; and a water containing reservoir closed at 10 the top and having a screw threaded lower end portion screwed into said ring and having a mouth communicating with said cup, said mouth extending into said cup below the upper edge thereof.
- 15 4. In a device of the character described, the combination with a sheet metal frame open at the top and bottom; of a cup supported by said frame; a wick supported by said frame and having portions extending 20 into said cup and other substantially horizontally disposed portions extending exteriorly of said cup; a ring attached to said frame; and a receptacle closed at the top and having an outlet at the bottom, supported 25 by said ring and extending therethrough with the lower end projecting into said cup and the outlet thereof disposed below the level of the upper edge of the cup.
5. In a device of the character described, 30 the combination with supporting means; of a cup mounted on said supporting means and open at its top; a substantially horizontally disposed wick supported by said supporting means having a portion thereof extending 35 into said cup and other portions extending exteriorly of said cup; a screw threaded ring mounted on said supporting means above said cup; and a reservoir communicating with said cup, said reservoir comprising 40 a glass jar having a screw threaded mouth, said jar being disposed in inverted position and having the mouth thereof screw threaded into said ring.
6. In a device of the character described, 45 the combination with a sheet metal frame open at the top and bottom, and provided with a pair of bottom flanges; of a screen
- closing the top of said frame; a second screen removably supported within said frame; a wick supported by said second screen; a source of water supply for said wick supported by said first mentioned screen; and means removably supporting said second named screen within said frame, said means including a one piece contractable wire 55 frame supported by said bottom flanges.
7. In a device of the character described, the combination with a sheet metal frame open at the top and bottom and provided with a pair of bottom flanges; of a screen 60 closing the top of said frame; a second screen removably supported within said frame; a wick supported by said second screen; a source of water supply for said wick supported by the screen closing the top 65 of said frame; and means removably supporting said second named screen within said frame, said means including a contractable rectangular wire frame having downwardly extending legs supported by said bottom flanges.
8. In a device of the character described, the combination with a rectangular sheet metal frame open at the top and bottom and provided with a pair of bottom flanges; of a screen closing the top of said frame; a second screen removably supported within said frame; a wick supported by said last named screen; a source of water supply for said wick supported by said first named screen; and means removably supporting said second named screen within said frame, said means including a one piece rectangular wire frame having downwardly bent portions at each corner forming legs adapted to be supported by said bottom flanges, one of said legs being composed of the opposite end portions of said wire, whereby said last named leg is separable so that the frame may be bent inwardly to contract the same. 90
- In witness that I claim the foregoing I have hereunto subscribed my name this 21st day of May, 1923.

JOHN SCHULZ.
